UNITED STATES PATENT OFFICE.

GERALD L. ABELL, OF OAKLAND, CALIFORNIA.

LIGHT, COLOR, AND RADIANT RAY BATH CABINET.

Application filed August 16, 1920. Serial No. 403,911.

My invention is an improved incandescent light and chromatic light bath cabinet.

An object of my invention and as provided for in the construction is the provision of light baths whereby the body as a whole may be treated in the cabinet or the various parts of the body may be subjected to light treatment by the direct application of the light to said parts. I provide a device which may be used for the head, a foot bath appliance, movable body bath attachments, and a seat with light treatment appliances in connection therewith.

My invention is illustrated in the annexed drawings which form a part of this specification.

Referring to the drawings,

Figure 1 is a front elevation of my invention.

Figure 2 is a plan view thereof.

Figure 3 is a horizontal section of my invention taken on line 3—3 of Figure 1.

Figure 4 is a vertical section of my invention taken on line 4—4 of Figure 3.

Figure 5 is a vertical section of the seat bath.

Figure 6 is a vertical section of the foot bath.

Figure 7 is a detailed section of the foot bath taken on line 7—7 of Figure 6.

Figure 8 is a side view of the seat emergency vessel.

My cabinet includes a main bath compartment 1, a head bath compartment 2, a seat

bath 3, a foot bath 4, and a body bath 5. The main compartment 1 is mounted on casters 7. The main compartment includes a floor 8, a front wall 9, side walls 10 and 11, back walls 12 and 13, and a top wall 14.

The back walls extend outwardly at an angle from the side walls 10 and 11 and meet midway between the side walls. The front, side and back walls rest upon the floor 8, and the top wall 14 rests upon the front, side and back walls. The walls of the main compartment are preferably made of wood.

An angle iron 15 covers the meeting corner of the front wall 9 and side wall 10 and is secured to said walls and to the floor 8 and top 14 at its lower and upper ends. An angle iron 16 covers the meeting corner of the front wall 9 and side wall 11 and is screwed to said walls and to the floor 8 and top 14 at its lower and upper ends. An angle iron

17 covers the meeting corner of the side wall 10 and the back wall 12 and is screwed to said

walls and to the floor 8 and top 14 at its lower and upper ends. An angle iron 18 covers the meeting corner of the side wall 11 and the back wall 13 and is screwed to said walls and to the floor 8 and top 14 at its lower and upper ends. An angle iron 19 covers the meeting corner of the back walls 12 and 13 and is screwed to said walls and to the floor 8 and top 14 at its lower and upper ends. Glass plates 20 are mounted on the inside of the front wall 9. Glass plates 21 and 22 are mounted on the inside of side walls 10 and 11. Glass plates 23 and 24 are mounted on the inside of back walls 12 and 13. In the front wall of the main compartment 1 is a front door 25 which is hinged by hinges 26 to one side of the front wall. The door is held closed by a latch 27. A glass plate 20 is mounted on the inside of the door 25. The forward portion of the top 14 is formed with an opening 28 which is closed by a pair of doors 29 and 30 hinged to top at the sides of the opening by hinges 31 and 32 respectively. An opening 33 is also formed rearwardly of the doors 29 and 30, partly in the top 14 and partly in the inner edges of said doors, through which opening the head of the occupant of the cabinet projects into the head bath compartment 2, which is made in the form of a hood and rests over said opening. The head bath compartment is hinged to the top 14 rearwardly of the opening by hinges 34. The front wall of the head bath compartment is a door 35 hinged at its upper edge to the upper wall of the compartment by hinges 36, which door may be opened to admit air into the cabinet. Incandescent electric lamps 37 are mounted inside the head bath compartment on the upper, side and back walls thereof. Vertical columns of incandescent lights 38 are mounted in the compartment 1. Other lights 38' are also mounted in the compartment. Adjustable parabolical hoods for housing incandescent electric lamps 39 are mounted in the compartment 1 for radiating light rays at the sides and in the rear of the seat, said lamps having interior and exterior light reflecting surfaces so that they absorb no light rays.

The seat bath 3 includes a standard 40, a seat frame 41, a lamp 42 and a seat 43. The standard 40 includes a base 44, which rests inside the cabinet 1 upon the cabinet floor 8, and a screw 45 upstanding from said base.

A hand wheel 46 screws on the screw 45. The seat bath may be raised or lowered by turning the hand wheel 46. The seat frame 41 includes a sleeve 47 which fits on the screw 45 and rests upon the hand wheel 46, and a lamp housing and seat support 48 extending upwardly from said sleeve. The part 48 has an external flange 49 at its upper edge and a plurality of openings 50 in the upper part of its side wall. The lamp 42 includes an upwardly directing parabolical reflector 51 and an incandescent electric lamp 42 screwed into a socket 53 in the bottom of the reflector. The reflector 51 rests within the housing 48 and has an external flange 52 at its upper edge which rests upon the flange 49 and supports the lamp 42 within the housing 48 with the bottom of the reflector resting slightly above the bottom of said housing to provide room for the contact 53' which engages the lamp contact 54. The reflector 51 has a plurality of openings 55 which register with the openings 50 through which openings heated air may escape providing ventilation below the seat 43. The openings 55 and 50 are controlled by a sliding damper 56. The seat 43 rests upon the reflector flange 52 and has a shoulder 60 which fits inside the reflector and holds the seat against lateral displacement on the seat support 48. The seat 43 is provided with an opening 61 and with a plurality of rabbets 62, 63 and 64 extending progressively outwardly from said opening at upwardly progressive levels. A wicker seat 65 is placed in the uppermost rabbet 64 flush with the top of the seat 43. A removable glass 66 which may be of various colors is mounted in the lamp reflector 51 below the openings 55 and 50. Sockets 67 and 68 are secured to the outside of the seat frame member 48 near the front and rear thereof in which sockets rest uprights 69 and 70 respectively. A rail 71 is secured at one end to the top of one upright 69 and extends rearwardly and in back of the seat and then forwardly, and is secured to the upper end of the uprights 70 and at its other end to the upper end of the upright 69. The uprights 69 and 70 and the rail 71 provide a back and arm support for the seat bath. An emergency pan 75 having an external flange 76 at its upper edge may be placed in the seat 43 within the opening 61 with said flanges resting in the rabbet 62 and supporting the pan. When the pan is used the wicker seat 66 is removed from the seat bath. The pan is adapted to receive the excretions of the kidneys of the patient sitting on the seat bath.

The foot bath 4 includes a tubular standard 80 formed with a base 81 secured to the floor 8, a screw 82 slidable in said standard, and an incandescent light bath receptacle 83 mounted on the upper end of said screw. A glass plate 84 covers the top of the receptacle 4, said plate being fitted in a rabbet 85 in the inner upper edge of the vertical walls of the receptacle. A wicker, such as the wicker 65 may be substituted for the plate 84. A glass reflecting plate 86 is placed in the bottom of the receptacle 83. Incandescent electric lamps 87 are mounted in the lower part of the receptacle 83 on the vertical walls of the receptacle, the light of which lamps is reflected upwardly by the reflecting plate 86 through the plate 84. Openings 88 are provided in the upper part of the vertical walls of the receptacle 83 through which openings the heated air may escape thus providing ventilation for the receptacle. The openings 88 are controlled by a sliding damper 89 having holes similar to damper 56. A gear 90 screws on the screw 82 and rests on the top of the standard 80 whereby the receptacle 83 is supported on the standard at the desired elevation. A lever 91 is pivoted at 92 to the standard 80 and carries a pawl 93 which engages the teeth of the gear 90. By rocking said lever the pawl 93 engages and escapes the teeth of said gear, whereby the gear is turned on the screw 82 and the receptacle 83 elevated.

The body bath 5 includes a receptacle 100 similar in construction to the foot bath receptacles and contains incandescent lamps 101. The receptacle 100 has two lugs on the back thereof through which extend a vertical rod 102 secured at its lower end to the swinging end of a horizontal arm 103, the other end of which arm is pivoted by pivot 104 to one end of a rigid arm 105 which is secured at its other end to the standard 106 of the column of lamps 38 in the left and right front corners of the compartment 1.

The floor 8 is provided with two air inlets 110 and 111 respectively at the sides of the seat bath 3, which inlets are controlled by dampers 112. An outlet flue 113 leads from the upper part of the main bath compartment 1.

The operation of my cabinet is as follows: When a person desires to enter the cabinet for treatment, the head bath compartment 2 is swung backwardly on its hinges 34 and the doors 25, 29 and 30 are swung open. The person enters the cabinet through the front thereof and sits on the seat 43 with his feet resting on the glass 84 of the foot bath 4 and his head projecting through the opening 33. The doors 25, 29 and 30 are closed and the head bath compartment is swung over the occupant's head. The electric current is then turned on. The lights 38 and 39 project their rays generally upon the occupant's body. The seat lamp 52 projects its rays upwardly upon the occupant's seat and privates. The lamps 37 project their

rays upon the occupant's head. The body bath 5 may be shifted about by means of the pivoted arm 103 and the rays of its lamps 101 directed to different parts of the occupant's body. The inlets 110 and 111 are open when the occupant takes a light bath and closed when he takes a heat and light bath.

The various light reflecting mirrors may 10 be glass or metal.

The main compartment may be opened or closed by the occupant within the cabinet.

Having described my invention, I claim:

1. In a light-bath cabinet of the character disclosed, a main light compartment, a front door in said compartment, doors in the front part of the top or roof of said compartment, the top of said compartment being provided with a head opening at the rear of said doors, and a head-bath compartment mounted and hinged on top of said main compartment, to be placed over said opening when it is occupied by the patient.

2. In a cabinet for therapeutical purposes, 25 a main compartment, an auxiliary head compartment hinged to the top of the main compartment, and an auxiliary seat compartment located within said main compartment directly beneath the head compartment, all of said compartments containing light disseminating means.

3. In a light-bath cabinet of the character described, a main compartment, a front door in said compartment, doors in the front of the top of said compartment, the top of said compartment being provided with a head opening at the rear of said doors, a head compartment hinged to the top of the main compartment so as to cover said opening, and auxiliary separate body, foot, and seat compartments located within said main compartment, all of said compartments containing light disseminating means.

4. In a cabinet for therapeutical purposes,

a main compartment for general treatment 45 of the body of a patient, a plurality of auxiliary compartments for treatment respectively of the head, body and feet of a patient, a floor for said main compartment provided with a plurality of air current controlling means and a top for said main compartment having a plurality of similar means.

5. In a therapeutical apparatus of the character described, a bowl, a reflector 55 therein, both opening upwardly, a light in the reflector, an open seat on the bowl and a baffle plate of light transmitting material interposed between the light and a body seated on the seat, for deflecting heat rays 60 from said body.

6. A device, as defined in claim 5, in which heated air is allowed to escape past the edge of the baffle plate and through controllable apertures in the side of the bowl.

7. A device as defined in claim 5, in which interchangeable colored elements are used for controlling the length of the light rays.

8. A device, as defined in claim 5, in which the seat is formed with annular stepped 70 ledges allowing a plurality of light or heat affecting media to be interposed under the buttocks of the body of the occupant.

9. A device, as defined in claim 5, in which the seat is removable and in which a flanged 75 receptacle may be made to rest on the top of the bowl below the seat.

10. A device, as defined in claim 5, in which the bowl rests on a threaded supporting element with projecting arms whereby 80 its height may be adjusted.

11. A device, as defined in claim 5 in which a removable back and arm support is secured to the bowl for the body of the occupant to lean against and support the 85 arms.

In testimony whereof I affix my signature.

GERALD L. ABELL.
